UNITED STATES PATENT OFFICE.

JOSEPH ELDER, OF PEORIA, ILLINOIS.

LOCOMOTIVE DRAW-BAR.

SPECIFICATION forming part of Letters Patent No. 391,233, dated October 16, 1888.

Application filed July 14, 1888. Serial No. 219,916. (No model.)

To all whom it may concern:

Be it known that I, JOSEPH ELDER, of Peoria, in the county of Peoria and State of Illinois, have invented certain Improvements in Draw-bars for Locomotives, of which the following is a specification.

To those familiar with the subject it is a well-known fact that great difficulty is experienced in maintaining a close connection between locomotive engines and their tenders, as the severe strains upon the draw-bar connecting them produce rapid wear of the bar upon the pins, so that a highly objectionable lost motion occurs between the engine and tender.

It is the aim of my invention to produce a simple and automatic device by which the draw-heads or buffers of the engine and tender may be drawn together and kept constantly in close contact; and to this end it consists, essentially, in a gravitating wedge introduced between the inner or rear face of the draw-head and the head or coupling-pin of the draw-bar, the wedge thus applied acting to pull the draw-bar into the draw-head.

I am aware that wedges have been driven between two draw-heads to force them apart, and that a horizontal wedge has been inserted behind the end of a coupling link or bar to force it outward tightly against the coupling-pin; but I believe myself to be the first to apply a wedge in such a manner that it acts to urge the draw bar into the draw-head, and thus maintain a contact between the two draw-heads, and therefore I do not limit myself to the precise form or arrangement of the details herein shown, although I have represented in the drawings those forms which I find best adapted for practical use.

My take-up device may be used at either or both ends of the draw-bar, as preferred; but I have deemed it sufficient to illustrate in the drawings the application at one end only.

In the accompanying drawings, Figure 1 is a vertical section through the draw-head for couplings of an engine and tender with my improvement applied thereto. Fig. 2 is a perspective view showing the various parts of a draw-head embodying my improvement separated from each other. Fig. 3 is a perspective view showing the draw-bar with its spheroidal head and bearing-plate.

Referring to the drawings, A and B represent the draw-heads or coupling-heads of the engine and tender, respectively; C, the draw-bar connecting them; D, the coupling-pin by which the bar is united to the draw-head of the engine, and E the vertical pin by which it is connected to the draw-head of the tender.

Instead of forming the draw-head B in the usual manner, I provide it in the rear side with a vertical opening or mortise adapted to receive a plate, F, through which the draw-bar is passed and against the rear face of which the coupling-pin is seated. Between this bearing-plate F and the inclined face b of the draw-head I insert the gravitating wedge G, which is forked in such manner as to straddle the draw-bar. The parts are so proportioned that when originally assembled with the draw-heads in contact the space between the plate F and surface b is so limited that it will only admit the thin end of the wedge, which is thus maintained in an elevated position. As the wear upon the eyes of the draw-bolt and coupling-pin produces end play between the parts, the wedge settles down by gravity, and by forcing the plate F away from the surface b urges the draw-bar endwise into the head B, thus compensating for or taking up the wear, so that the contact between the heads is maintained. In order to prevent the wedge from working upward under the pressure and vibration of the parts, I incline its rear face downward and rearward and give the corresponding face of the plate F a like inclination, as shown in Fig. 1, so that the plate by its pressure tends to prevent the rising of the wedge. It is to be understood, however, that this is not a vital feature of my construction.

In place of the coupling-pin E, I may form on the end of the draw-bar a head or enlargement, such as shown at e, Fig. 3, in which case the draw-bar must be inserted endwise through the plate F from the rear side. The plate F is in such case formed with a concave face corresponding with the face of the head e, this arrangement permitting the bar to swing both laterally and vertically, as the relative movements of the engine and tender may require, without the loosening of the parts. When the draw-bar is shown, as in Fig. 3, with a head, e, on one end and the eye on the

other, the take-up wedge may be applied at one end, as in Fig. 1, and at the other end, as in Fig. 3.

The essence of my invention resides in the application of the wedge to the draw-bar or link in such manner that the link is urged endwise into the head.

Having thus described my invention, what I claim is—

- 10 1. In a take-up for railway draw-bars, the combination of a draw-head, a draw-bar, and an intermediate wedge, substantially as described, acting to urge the draw-bar endwise into the head.
- 15 2. In a take-up mechanism for railway draw-bars, the combination of the draw-head B, having an inclined surface, b, the draw-bar, the plate F, attached to the draw-bar, and the gravitating wedge G, located between the front 20 of said plate and the draw-head, as shown.

3. The combination, with the draw-head having the inclined surface b, of the draw bar, the wedge G, and the plate F, connected to the draw-bar, having its front face inclined upward and forward to overhang the wedge, as described, whereby the accidental rising of the wedge is prevented.

4. In combination with the two draw-heads, each having a gravitating wedge and a plate, F, therein, the draw-bar, having at one end the head or enlargement e and at the opposite end an eye or opening, and the coupling-pin inserted through said opening, as shown.

In testimony whereof I hereunto set my hand, this 3d day of March, 1888, in the presence of two attesting witnesses.

JOSEPH ELDER.
